UNITED STATES PATENT OFFICE.

AMBROSE CLARK MOORE, OF CHICAGO, ILLINOIS, ASSIGNOR TO CHICAGO RAILWAY EQUIPMENT COMPANY, OF CHICAGO, ILLINOIS, A CORPORATION OF ILLINOIS.

CONNECTING-ROD SAFETY LOOP.

Application filed November 27, 1925. Serial No. 71,643.

This invention relates to new and useful improvements in safety loop supports or hangers for brake beam connecting rods and has for its object the provision of a 5 safety loop support adapted to be attached to a carrying member and provided with a depending portion terminating in a loop adapted to encircle or partially embrace the bottom connecting rod of the brake gear, 10 the end or ends of said safety loop support being adapted to enter interlocking engagement with each other or with said carrying member to render said support immovable on said carrying member.

15 Further objects of the invention are to provide a safety support or hanger having one portion formed to detachably embrace a carrying member, such as a brake beam part, or spring plank and having a depending portion looped to extend under and upwardly on each side of a bottom connecting rod for catching and supporting said rod in case of its disengagement at either one of its ends.

20 Still further objects of the invention are to form the upper portion of said safety support or hanger with a bent terminal portion or portions so as to lock said loop safety support or hanger against accidental displacement from said carrying member.

25 With these and other objects in view, my invention consists in certain novel features of construction and arrangement of parts, hereinafter more fully described and 30 claimed, and illustrated in the accompanying drawings, in which—

35 Figure 1 is a vertical cross section through a portion of a car truck and showing the safety loop carried by a brake beam 40 part and engaging the bottom connecting rod.

Figure 2 is a view taken on line 2—2 of Figure 1.

Figure 3 is a view similar to Figure 2 45 showing a modified form of safety support.

Figures 4 to 9 show other modified forms of safety supports or hangers for bottom connecting rods.

50 Figure 10 shows another modified form of the loop support having one end connected to the compression member of the brake beam and the other end to the tension member thereof.

Figure 11 is a vertical section taken on line 11—11 of Figure 10. 55

Figure 12 is another modified form of safety support and hanger carried by the compression and tension members of the brake beam and having its rod engaging portion formed in the shape of a closed ring. 60

Figure 13 is a section taken on lines 13—13 of Figure 12.

Referring by numerals to the accompanying drawings and more particularly to Figures 1 and 2, 10 indicates the spring plank 65 of a car truck and 11 indicates a brake beam consisting of a compression member 12, tension member 14, and strut 15. A brake lever 16 is pivotally mounted in the strut and has its lower end pivotally connected to one end 70 of a bottom connecting rod 17 which is horizontally disposed under the spring plank and the brake beam and has its opposite end connected to a brake gear connection similar to the one shown in the drawings. 75 All of the parts are of any approved construction and are standard equipment of railway cars.

In order to prevent said bottom brake rod from dropping to the ground in case one 80 of its ends becomes accidentally disengaged from its respective lever or connection, a safety support or hanger 18 is arranged on a suitable carrying or supporting member such as a brake beam part, in the present instance compression member 12, and said 85 hanger is provided with a depending portion 19 terminating in a loop or eye 20 which encircles said brake rod and normally is spaced therefrom so as not to impede its 90 operative movements and is adapted to form a support therefor in case of displacement thereof.

The compression member engaging portion 21 is bent horizontally over said member and then downwardly and has its end hooked as indicated at 22 and bent under said compression member so as to engage shank portion 23 of said support. In this manner, the support or hanger is locked in 100 position on the compression member and is held against movement longitudinally of said member by the resiliency of said support member, portion 21 and shank 23 being stressed when interengaged with each other. 105

In the form shown in Figure 3, hanger 24

is provided with a loop 25 for encircling the bottom connecting rod and the extreme end of said loop portion is provided with a hook 26 for engaging the opposite end 27 of member 24.

In the form shown in Figure 4, member 28 is formed with a loop 29 for engaging bottom connecting rod 17 and one leg of said member extends upwardly and is bent laterally as indicated at 30 and bears against the upper face of compression member 12. The other leg is bent laterally as at 31 and extends under the compression member 12 and upwardly on opposite side thereof and is rebent to form a shouldered portion 32 which is adapted to fit between the spaced flanges 12^a of member 12. The extreme end of this rebent portion projects upwardly to one side of compression member 12 as indicated at 33 and is adapted to be engaged by the hooked portion 30^a of laterally disposed portion 30. By interengaging the rebent portion of the loop support with the flanges of the carrying member, said loop or hanger is securely held against movement in either direction.

In the form shown in Figure 5, the safety support or hanger 34 is provided with a U-shape portion 35 for engaging the bottom connecting rod 17. The legs of this portion extend upwardly and are bent at a point below the carrying member 12 so as to cross each other and extend upwardly on the opposite sides of said member as shown at 36. These portions 36 are bent at right angles to bear against the upper face of carrying member 12 as shown at 37 and have their ends bent at an angle to portions 37 to extend downwardly on each side of said carrying member 12. When placed in position, portions 36 are stressed and are spring-held in engagement with the carrying member, thereby preventing rattling of the support and maintaining the latter in position.

In the form shown in Figures 6 and 7, the hanger 38 has its upper portions bent as indicated at 39 to bear at a plurality of points against the peripheral face of a carrying member, which in the present instance is circular in cross section, and the extremities of portions 39 are rebent to form interlocking engagement as indicated at 40.

In the form shown in Figure 8, one leg of loop member 41 extends upwardly to one side of carrying member 12 and is bent horizontally as indicated at 42 over said member 12 and has a rebent portion 43 which bears against the underside of the upper flange of member 12. The other leg of said member extends upwardly to the opposite side of said member 12 for engaging the edge of the lower flange and terminates in a hook 44 which is adapted to engage eye 45, which latter is formed in the extremity of portion 43.

In the form shown in Figure 9, a support member or hanger 46 has its lower end terminating in a brake rod receiving portion 47 and the upper portion of said support member extends upwardly and is provided with a horizontal portion 48 which bears on top of the support carrying member 12 and terminates in a rebent portion 49 which bears against the underside of the upper flange of said member 12. A bend 50 is formed in the shank of member 46 to increase the resiliency of said member so that sufficient pressure is exerted against said supporting member 12 by said member 46 to prevent movement or vibration of supporting member 46.

In the form shown in Figures 10 and 11, a member 51 is formed of a single piece of material, preferably circular in cross section, and is provided with a portion 52 for surrounding the bottom connecting rod 17. One end of member 51 is bent rearwardly and terminates in a portion 53 for partially engaging compression member 12 while the opposite end of member 51 is bent downwardly and terminates in a portion 54 for partially engaging the tension member of the brake beam. Portions 53 and 54 are formed resilient so as to engage the respective supporting members under spring pressure.

In the modified form shown in Figures 12 and 13 member 55 instead of being formed of a single piece of wire or wood is formed of a casting or forging and consists of a longitudinally disposed portion 56 the ends of which terminate in portions 57 and 58 for engaging the compression member 12 and tension member 14, respectively, and is provided with a depending portion 59 terminating in a closed ring 60 through which the bottom connection rod 17 is adapted to operate.

I claim:

1. A brake connecting rod support formed of a single piece of material and having interlocking resilient end portions for detachably engaging a supporting member, and a depending portion adapted to encircle a connecting rod of a brake gear.

2. A single piece support for connecting rods comprising a resilient end portion the elasticity of which will enable it to tightly engage a carrying member, and provided with a depending loop portion adapted to encircle said connecting rod.

3. A connecting rod support comprising a member having a depending portion adapted to partially embrace a brake connecting rod and provided at its upper end with resilient rebent portions for detachably engaging a carrying member.

4. A safety support for brake beam connecting rods comprising a member having a resilient portion adapted to engage under tension a brake beam member and having a

depending portion adapted to extend under and encircle a connecting rod in spaced relation therewith.

5. In a safety support for bottom connecting rods for brake gears, the combination of a carrying element, a movable element extending under and transversely of said carrying element, and a single piece safety support member having a resilient portion adapted to enter into tensioned supporting engagement with said carrying element and having a depending loop portion extending under and on the sides of said movable element and normally in spaced relation therewith to allow movements of said elements relatively to each other and adapted to connect and support the same in case of accidental displacement thereof.

6. A connecting rod support loop formed of a single piece of material and having a resilient portion for detachably engaging by its own resiliency a carrying member, and a depending portion adapted to encircle and support a connecting rod.

25 7. A single piece support for connecting rods having integral resilient portions adapted to engage by their own resiliency a carrying member and having a depending loop portion adapted to extend under and on the sides of a connecting rod in spaced relation therewith.

8. A connecting rod support extending under a connecting rod and having rebent ends for resiliently engaging a carrying member.

35 9. A single piece support for bottom connecting rods of brake gear having a portion adapted to support said connecting rod and having resilient end portions adapted to engage by their own resiliency a flanged carrying member.

10. A single piece support for connecting

rods having a loop portion extending under said rod for supporting the same and provided with resilient end portions overlying a carrying member and having its extremities rebent for resiliently engaging said carrying member and securing said support in position on said carrying member.

45 11. A safety support for connecting rods having a loop portion adapted to underlie a connecting rod and terminating in a spring hook for resiliently engaging a carrying member.

12. A single piece emergency support for bottom connecting rods for brake beams having a loop portion for encircling said connecting rod and having its ends disposed above said rod and adapted to be stressed to resiliently and detachably engage a brake beam member.

55 13. A brake connecting rod hanger formed of a single piece of spring material having a portion for yieldingly engaging a supporting member and having a portion adapted to carry a brake connecting rod.

65 14. A brake connecting rod hanger formed of a single piece of spring material comprising a portion adapted to pass over the top of a supporting member, a portion yieldingly engaging the sides thereof, and a depending portion adapted to carry a brake connecting rod.

70 15. A brake connecting rod hanger formed of a single piece of spring material adapted to pass over the top of a supporting member and yieldingly engage the top, sides and bottom of said member and having a depending portion adapted to carry a brake connecting rod.

75 In testimony whereof I hereunto affix my signature this 23rd day of November, 1925.

AMBROSE CLARK MOORE.
